CELLOPHANE TAPE DISPENSER

David Belbow, 1485 Pine St., San Francisco, Calif.

Filed Mar. 2, 1961, Ser. No. 64,127

Term of patent 14 years

(Cl. D74—1)

FIG. 1

The broken lines showing of the roll of tape are for illustrative purposes only.

I claim:

The ornamental design for a cellophane tape dispenser, as shown and described.
